UNITED STATES PATENT OFFICE.

FRANCESCO CIRELLI, OF PHILADELPHIA, PENNSYLVANIA

SOUND-REPRODUCING MACHINE.

1,302,900.

Specification of Letters Patent.

Patented May 6, 1919.

Application filed August 27, 1917. Serial No. 188,540.

To all whom it may concern:

Be it known that I, FRANCESCO CIRELLI, a citizen of the United States, residing at Philadelphia, in the county of Philadelphia and State of Pennsylvania, have invented certain new and useful Improvements in Sound-Reproducing Machines, of which the following is a specification.

My invention relates to improvements in sound reproducing machines the object of the invention being to provide a machine of the character stated which dispenses altogether with the ordinary horn, which may be readily carried from place to place, and occupy but relatively small space.

A further object is to provide an improved construction of box in which the sound waves are directed by a tone arm into a chamber having perforated walls located at one end of the box, leaving a chamber at the other end, or front portion of the box, for the turn table and record disks.

A further object is to provide a sound reproducing machine of the character stated which provides a drawer for the accommodation of the tone arm and sound box when disconnected from normal position, and permits the assemblage of record disks on the turn table where they can be conveniently supported when the machine is to be moved from place to place.

With these and other objects in view the invention consists in certain novel features of construction and combinations and arrangements of parts as will be more fully hereinafter described and pointed out in the claims.

In the accompanying drawings:

Figure 1 is a perspective view illustrating my improvements.

Fig. 2 is a view in longitudinal section.

Fig. 3 is a view in transverse section.

Fig. 4 is a view in section on the line 4—4 of Fig. 2, and Fig. 5 is a fragmentary sectional elevation showing certain of the coupling parts in register with each other.

1 represents my improved box, and 2 a hinged cover thereon. The box 1 is to contain any improved motor (not shown) and a sliding drawer 3 is provided in one end of the box which is as deep as the space will allow. A horizontal platform 4 is secured in the box 1, and spaced from the upper edge thereof. A curved wall 5, extending transversely of the box 1, supports horizontal removable plates 6, 6, which together

with the wall 5, constitutes a sound distributing chamber 9. The walls 5 and plates 6 are perforated as shown at 7, to allow the sound to escape in all directions. The hinged cover 2 when supported in open position by the supporting member 8 acts as a deflector or sound board to throw the sound toward the front end of the box.

In the center of the sound distributing chamber, a collar 10 is supported and elevated above the bottom of the chamber so that the sound waves can freely pass into the chamber. This collar 10 extends above the plates 6 and is connected by a removable coupling ring 11, with the tone arm 12. The coupling ring 11 is provided with a plurality of recesses 13 which when aligned with projections 14 on the collar, permits the tone arm to be disconnected, but when the coupling ring is turned slightly the tone arm will be secured in operative position.

In Fig. 5 I have illustrated in sectional elevation the relation of the projections 14 and recesses 13 when they are in register with each other. For example, this view of drawing shows the coupling ring 11 having been moved downwardly so that the recesses 13 permit the projections 14 to occupy the space within said coupling ring 11. By turning the coupling ring 11 in either direction from the position shown in Fig. 5, the recesses 13 will be moved out of register with the projections 14 and the projections 14 will thereby be confined within the coupling ring and prevent the tone arm from being moved out of its proper relation with the collar 10.

It will be noted that the outlet end of the tone arm is enlarged and that the upper portion of the ring 11 is adapted for engagement with a portion of the tone arm which is of less diameter than the extreme outlet end thereof. Thus when the ring 11 is coupled to the collar 10 it also confines the enlarged outlet end of the tone arm 12.

A pin 12^a is mounted in the tone arm 12 and normally rests upon the upper edge of the coupling ring 11. This pin 12^a forms a stop or limiting member to prevent the tone arm from moving bodily downward within the collar 10.

The chamber 15, formed between walls 5 and the side walls of the box 1, constitutes a housing or receptacle for the turn table 16 which supports record disks 17. The tone arm 12 carries any improved sound box 18

with its stylus 19 to engage the disk 17, and reproduce sound in the ordinary way.

The side walls 20 of the box 1 extend above the horizontal plane of the turn table, 5 and turn buttons 21 are provided on the side walls which are adapted to be moved inwardly and clamp a plurality of record disks 17 on the turn table 16. This is desirable when carrying the box from place to place, 10 as it provides room for several records.

When transporting the box it is necessary to first disconnect the tone arm 12 and locate the same in the drawer 3, when the cover 2 can be closed and the box will occupy but 15 small space.

In operation the sound waves from the tone arm 12 are directed into the chamber 9, and find an outlet through the perforations 7, hence the sound waves pass upwardly 20 through plates 6 and horizontally through the wall 5, the cover 2 acting as a sound board or deflector to direct the sound waves to the open end of the box.

Various slight changes may be made in 25 the general form and arrangement of parts described without departing from my invention and hence I do not limit myself to the precise details set forth, but consider myself at liberty to make such changes and 30 alterations as fairly fall within the spirit and scope of the appended claims.

Having fully described my invention, what I claim as new and desire to secure by Letters Patent is:

35 1. A sound reproducing machine including means providing a platform; a tone arm movably supported by the platform and hav-

ing its outlet end adapted to direct the reproduced sounds toward the platform so that said sounds impinge upon said platform; a perforated plate spaced above said platform at the position where said sounds impinge thereon; and a wall extending between said perforated plate and the platform, said wall having perforations therein 45 extending at an angle to the perforations of said plate for deflecting a portion of the sound forwardly, substantially as described.

2. A sound reproducing machine including a box having a platform therein; a collar 50 having an open lower end spaced above said platform; a tone arm movably supported by said collar and adapted to transmit sound out of said lower end of the collar; a perforated plate mounted above said platform 55 and extending around said collar whereby the sound passes through said tone arm and out of the open end of said collar, then impinges upon said platform, and finally passes upwardly through the perforations of said plate; and a curved wall extending between said platform and said perforated plates, the curve of said wall extending forwardly in a plane substantially parallel with said platform having perforations extending at 60 an angle to the perforations in said plates, substantially as described.

In testimony whereof I have signed my name to this specification in the presence of two subscribing witnesses.

FRANCESCO CIRELLI.
